CLASSIFICATION SYSTEM

Willing B. Foulke, Media, Pa., assignor to E. I.
du Pont de Nemours & Company, Wilmington,
Del., a corporation of Delaware

Application January 21, 1937, Serial No. 121,386

9 Claims. (Cl. 209—172)

A. This invention relates to the separation of solids of different specific gravities by the use of a liquid of intermediate specific gravity. The invention has particular application to the separation of coal from its indigenous impurities and it will be described in that connection, but that particular description is illustrative, not limiting.

B. In copending application, Alexander et al., filed August 31, 1936, Serial No. 98,818, there is described a new process and a new apparatus for carrying out the separation of materials of different specific gravities. In that invention coal is wetted with an aqueous solution containing a proportion of an active agent, an example of which is tannic acid, and is immersed in a separating fluid of specific gravity intermediate the specific gravities of the coal and the impurities. The classified materials are removed separately from the apparatus and the washing fluid is treated in a particular, inventive manner for the recovery of the parting liquid.

C. It is an object of this invention to separate coal from slate and other minerals from impurities by an improved process. Another object of the invention is to carry out the improved process or the process described in said earlier filed application by an improved apparatus. Other objects of the invention will be in part elsewhere herein described and in part apparent.

D. The objects of the invention are accomplished, generally speaking, by subjecting the materials to be separated to the action of a moving stream of light liquid, such as water, and thereafter subjecting the so-classified materials to the action of a liquid body having specific gravity intermediate the specific gravities of the materials to be separated. The objects of the invention are also accomplished to a degree by the details of the apparatus and method more fully hereinafter described.

E. In the drawings Figure 1 is a plan view of the apparatus; Figure 2 is a section on the line 2—2 of Figure 1; Figure 3 is a section on the line 3—3 of Figure 1; Figure 4 is a section on the line 4—4 of Figure 2; Figure 5 is a section on the line 5—5 of Figure 2; Figure 6 is a section on the line 6—6 of Figure 2, and Figure 7 is a detail of the means of sealing removable covers of the apparatus.

F. In the drawings, 10 is an enclosed tank; 11 is a sump; 12 is an inclined portion in the bottom of the tank leading upwardly and forwardly from the bottom of the sump; 13 is a weir; 14 is a compartment formed by the bottom of the tank 10, weir 13, and wall 15; 16 is an inclined bottom of the tank beyond the wall 15; 17 is an end pipe forming a tank wall. By this construction there is provided what are in effect two tanks, the first of which, having inclined bottom 16, will be called the first tank, and the second

of which, having an inclined bottom 16, will be called the second tank. 18 is a slot in the wall 17 which permits the exit of the screen; 19 is a tank-like extension of the chamber 10; 191 is an end wall of tank 10 which extends downward into the tank 19 to a position below that normally occupied by the liquid of tank 19; 101 is an outer wall of the tank enclosing the recovery apparatus and screen.

G. Referring to the liquid handling portion of the apparatus, 20 is a pipe leading from a supply of the parting liquid which is to be used to effect the classification; 21 is a valve; 22 is a valve in pipe 23; 24 is a pipe connecting pipes 20 and 23 with sump 11; 25 is a pump in pipe 23; 26 is a pipe connecting chamber 14 with settling tank 27; 28 is a pipe connecting the lowest point of tank 16 with sump 11; 29 is a pipe extending from the liquid level in tank 16 to tank 27; 192 is a pipe and 193 is a valve therein whereby to fill and drain tank 19. Settling tank 27 has an inclined bottom 270; 271—272 are perforated baffle plates forming a chamber within which the pipes 26 and 29 may discharge; 273 are inclined perforated baffle plates in the settling tank; 274 is an imperforate baffle extending below the liquid level of the tank; 275 is a weir across the end of the tank; 276 is a pipe leading from the chamber beyond the weir; 277 is a pump in the pipe 276; 278 is a pipe; 279 is a valve therein; 280 is a pipe connecting pipes 278 and 276 with sprays 281; 282 are flexible baffles between adjacent sprays; 283 is a second pipe leading from pipes 276 and 278; 284 are sprays placed beneath the screen for operation thereagainst; 285 is a pipe opening at 286 into the tank 16 and at 287 into the tank 12; opening 287 is at least in part above the level at which the parting liquid is maintained in the tank 12.

H. Referring now to the mineral-handling equipment, 30 is a chute; 31 is an opening from the chute through the side of the tank 12; 32 is a baffle extending from above the opening 31 to proximity to the bottom 12; 320 is a flap, preferably flexible, attached to the lower end of baffle 32; 33 are a series of rollers; 35 is a wire screen, which may be of Fourdrinier, wedge wire, or any other satisfactory type, trained around the rollers 33. The wire passes about one roller 33, through an opening 330 in the tank 10, in back of the baffle 32, around roller 33, and beneath the baffle whose flap 320 makes contact with the upper surface thereof and prevents solids from piling up against the roller 33, passes over the series of small rollers 33 and over the chamber 14 and wall 15 and about tank 16, around end rollers 33 through slot 18 in wall 17, and back beneath the tanks over adjustable roller 33a. Other rollers may also be made adjustable in known ways if it is desired. One such way is in

proximity to opening 330. 36 is an angle-shaped partition dividing the screen and closely conforming to the surface thereof; 35 is a screen baffle extending from the forward end of the opening 31 to the partition 36, the bottom edge of the said screen being beneath the surface of the parting liquid but not so close to the screen that materials would be prevented from passing beneath it. 37-38 are side guards to prevent materials from jamming between the screen and the sides of the tank and to prevent wear on the tank sides. 40 is a scraper type discharge conveyor operating in the water-sealed tank 19; 41 is a partition in the tank 19 which in effect divides the conveyor into two parts; 50 is a framework within the tank; 51-51 are shafts mounted in the framework bearing rollers 52-52; 53 are belts trained over the rollers; 54 are rakes carried by the belts; and 55 is a motor and connections 20 for driving the shafts, the wheels, the belts, and the rakes.

I. The operation of the device will be described by following through the apparatus the various materials and the functions which they perform 25 or which are performed upon them. Assuming that the material to be classified is run-of-the-mine anthracite coal, which contains of course a certain amount of admixed slate, dirt, and other impurities, the tank 12 will be filled with heavy 30 liquid having a specific gravity between that of the coal and that of the main impurity to the heavy liquid level through pipe 20. Thereafter water will be run in on top of the heavy liquid until a blanket is formed. The run-of-the-mine 35 coal will be admitted through the opening 30 and opening 31, the sprays 281 will be started, and the tank 16 will be filled until water runs through the opening 286 down the pipe 285 and through the opening 287 which is beneath point 40 31 of admittance for the coal. As the water enters through opening 287, it has considerable velocity and moves in a stream across the surface of the heavy liquid carrying with it to the other side of the apparatus all materials which float 45 on the heavy liquid and serving to give a preliminary hydraulic classification to the solids before they are acted upon by the heavy liquid. The entire apparatus being started, the material heavier than the liquid, which will hereinafter be 50 called sinks, falls from the opening 31 through the water issuing from opening 287 and toward the bottom of the tank 12. Some of it encounters the baffle 32 and all of it eventually encounters the moving screen 34 and a point in proximity to the point of admittance. The sinks are 55 picked up by the screen, carried beneath the baffle screen 35, and over the wall 15 to the showers 181. The partition 36 confines the sinks to and on the side of the apparatus. The material which floats upon the surface of the heavy liquid is carried by the stream of water over and past the partitions 36 and 381 to the other side of the machine. The rakes catch the material and drive it forward until it makes contact with 60 the moving screen which picks it up and takes it to the showers.

J. The sprays from the showers impinge both from above and beneath and thoroughly wash the material, freeing it from parting liquid transported on its surface. The wash water and the mixed heavy liquid are caught in the tank 16; the heavy liquid settles out at the low point of the tank and is carried through pipe 28 to sump 11. The pipe may be left open constantly or may be 65 opened from time to time by means of a valve

if it is desirable. Having passed beneath the showers, the coal is discharged over the roller 33 into the water-sealed tank 19 where it is picked up by the scraper conveyor 40, which is divided by the partition 41 into two parts, one for sinks 5 and one for floats.

K. The heavy liquid in the tank 12 is maintained at its level by that returned through pipe 28 and by the admission of other heavy liquid through pipe 24. The level of the water in the 10 system is maintained by weir 13 in conjunction with water admitted through pipe 285. The water, reaching the level of the weir 13, flows into the chamber 14 and through pipe 26 to settling tank 27. Baffles 272 and 271 form a turbulence 15 chamber within the tank 27, within which the turbulence caused by the entry of the liquid is absorbed, the liquid in the remainder of the tank flowing quietly. The perforated baffles 271, 272, and 273 act upon the flowing liquids to separate 20 the heavy from the light liquid. The heavy liquid sinks to the bottom of the tank which is provided with an inclined bottom 270 and is withdrawn from the lowest end thereof through pipe 24 and is returned through pipe 23 to the sump 11. The 25 screen passes out of the water before it passes the wall 15 and a first washing takes place in the water of tank 12, a first draining takes place above chamber 14 and, consequently, a large portion of heavy liquid is caught in chamber 14 30 and tank 12. Passing the wall 15 between the two tanks, the screen carries the material beneath and above a series of showers which free it from the remaining heavy liquid. The wash water from tank 16 passes through opening 286 35 or, if that opening is incapable of absorbing the entire quantity, through pipe 29 whose opening is at the level of opening 286 to the turbulence chamber of tank 27. The liquids, bled substantially free from heavy liquid by the baffles 273, 40 passes beneath the imperforate baffle 274 which excludes light floating materials from the weir chamber beyond weir 275, and over the weir 275 from whence it is withdrawn through pipe 276 and used again in the showers.

L. The side guards 37 and the partition 36 are worn in to the surface of the screen by permitting light contact during the first operation of the screen. Thereafter the fit is so close that it is only exceptionally that solid materials get between it and the screen. In order to take care 50 of such solid materials, these partitions are made so that they are self-freeing. This is accomplished by making the partitions narrower toward the discharge end of the machine. In that way 55 a particle caught between the screen and the board is carried in the direction of the screen and constantly approaches a narrower part of the board until it is finally discharged from beneath it.

M. By this invention there is produced an efficient apparatus and process for the classification of solids. The unit is efficient, self-contained, and subject to wide variation in detail without departing from the scope of the invention.

N. As many apparently widely different embodiments of this invention may be made without departing from the spirit and scope thereof, it is to be understood that I do not limit myself to the specific embodiments thereof except as 70 defined in the appended claims.

I claim:

1. In the process for the classification of solids an hermetically sealed chamber containing separated tanks, means to admit a liquid to one said 75

- 5 tank, means to maintain the liquid level comprising a weir and compartment, means to flow a second liquid upon the first, means for removing solids comprising a movable screen operating in proximity to the bottom of the first and above the second tank, means in part submerged for partitioning the screen, means at one side of the partition to admit solids to the flowing liquid, the flow of the liquid being so directed that the floats will be carried beyond the partition before encountering the screen, means above the second tank to wash the separated solids, a settling tank having means for separating liquids of different densities, means 10 connecting the weired compartment and the said other tank with the settling tank, means for returning heavy liquid to the first tank, and means for supplying light liquid to the said washing means.
- 15 6. In a process for the classification of solids an hermetically sealed chamber containing separated tanks, means to admit a liquid to one said tank, means to maintain the liquid level comprising a weir and compartment, means to flow a second liquid upon the first, means for removing solids comprising a movable screen operating in proximity to the bottom of the first and above the second tank, means partitioning the screen, means at one side of the partition to admit solids to the flowing liquid, the flow of the liquid being so directed that the floats will be carried beyond the partition before encountering the screen, means above the second tank to wash the separated solids, a settling tank having means for separating liquids of different densities, means to direct 20 the wash liquid thereto and means for recovering heavy liquid.
- 25 7. An apparatus comprising a plurality of tanks, means to admit a parting liquid to one said tank, means to admit solids to said tank for classification, means for removing the classified solids from said first tank to a position above another of said tanks comprising a screen, means comprising a transversely directed stream of water for directing the classified solids to different portions of the screen, means for washing the classified solids on the screen, means for separating parting liquid from the wash liquids in the second tank, means for returning the parting liquid to the first tank, and means for reusing the wash liquid.
- 30 8. The process which comprises plunging a mass containing particles of different densities into a stream of water having sufficient depth and velocity to produce an initial horizontal classification and thereafter subjecting the particles of the mass in the relationship produced by the said stream to the vertical classifying effect of a still body of a liquid having a density between the densities of the said particles.
- 35 9. The process which comprises plunging a mass containing particles of different densities into a stream of water having sufficient depth and velocity to produce an initial horizontal classification and thereafter subjecting the particles of the mass in the relationship produced by the said stream to the vertical classifying effect of a body of a liquid having a density between the densities of the said particles.
